UNITED STATES PATENT OFFICE.

EDGAR REAGAN, OF FLORESVILLE, TEXAS.

COTTON CLEANING AND CONDENSING MACHINE.

No. 802,114.

Specification of Letters Patent.

Patented Oct. 17, 1905.

Application filed September 20, 1904. Serial No. 225,224.

To all whom it may concern:

Be it known that I, EDGAR REAGAN, a citizen of the United States, residing at Floresville, in the county of Wilson and State of Texas, have invented certain new and useful Improvements in Cotton Cleaning and Condensing Machines, of which the following is a specification.

This invention relates to cotton cleaning and condensing machinery; and it has for its object to provide a simple, durable, and comparatively inexpensive machine for cleaning the cotton fiber and forming it into a bat as it leaves the gin in preparation for the baling press; and it consists of the parts and combinations of parts hereinafter described and claimed.

In the accompanying drawings, forming a part of this specification, Figure 1 is a side elevation of my improved machine; Fig. 2, a similar view with the side frame of casing removed, and Fig. 3 a detail view of a portion of the drum and concaved screen.

Similar letters refer to similar parts throughout all the views.

Referring to the drawings, A represents the casing for the machine, which is preferably formed with the curved top and the inclined or converging bottom having an opening provided with a hinged door B for the removal of the dirt and trash which accumulates therein during the operation of the machine. At its discharge end the casing is provided with a hinged door C, with a pane of glass framed therein, whereby access may be had to the interior of the casing when desired and also the operation of the machine observed. At the opposite or receiving end of the casing a feed - chute D is provided, which connects with the ginning machinery and delivers the cotton therefrom to the cleaning mechanism, said chute being provided with a glass-covered observation - opening E. The cotton lint is carried through the chute D by the blast from the gin. Arranged and suitably supported within the casing is a concaved screen F. This screen may be of wire mesh with transverse ribs G secured in any preferred manner thereon, or it may be of perforated sheet metal. The ribs G may be formed by fluting the material out of which the screen F is formed, if preferred. A drum H, composed of perforated sheet metal or wire-gauze, having fingers a secured in rows at suitable distance apart, is secured on a shaft b, which extends through the sides of the

casing and has its bearings in adjustable journal-boxes c, which are supported outside the casing on the diagonal bars d, which extend across the casing. The fingers a are preferably formed with shoulders which abut against the surface of the drum and with reduced and threaded ends which extend through the drum in order to receive a nut e thereon to hold the fingers in place. In Fig. 2 is shown the end of one of the fingers with the nut thereon. The drum H is arranged over the concaved screen F and may be adjusted toward or from either end of said screen in order to regulate the thickness of the bat passing therebetween. This is accomplished by means of the screw - rods f, which extend through threaded split collars g, secured in the frame of the casing at each side to lugs h on the sliding bearing c, said boxes being slidably held on the bars d by means of bolts i, secured to said bars and extending through slots j in the boxes c and having nuts thereon to guide and hold the boxes in position. The rods f are formed or provided with crank-handles whereby they may be easily turned, and when turned move the boxes along the rods d toward either end of the concaved screen, as desired.

K represents the upper receiving - roller, and L the lower receiving - roller. These rollers are arranged at the discharge end of and within the casing and receive the lint from the drum H and compress the same into a bat. The upper roller K is secured on a shaft which has its bearings in boxes l, arranged on and adjustable along the bars d, to or from the drum H and to or from the lower roller L. The boxes l are formed with slots m, through which threaded bolts n are secured to bars d, and fastening-nuts are run thereon to hold the boxes in their adjusted positions. The lower roller L is carried by a shaft which has its bearings in boxes M, arranged on the inclined bars N of the frame, said boxes M being formed with slots and bolts provided therefor, so that they may be adjusted on the rods N in a manner similar to boxes l.

A condensing-roller O is arranged opposite the lower roller L and presses against the bat, passing therebetween. The shaft of roller O is journaled in the curved arms P, which are pivotally suspended or hung from the uprights Q at each side of the casing, the lower ends of said arms being formed with openings through which a threaded rod R

extends and has its end loosely attached to a lug *p* on the boxes *M*. At the outer or free ends of the rods *R* coiled springs *S* are arranged which bear against the ends of the arms *P* and are held in place on said rods and their tension adjusted by means of the thumb-nuts *T*, run on the ends of said rods *R*.

The driving mechanism consists of a pulley *U*, secured on the drum-shaft *b*, which 10 may be connected to any suitable prime mover. The shaft *b* also carries a sprocket-wheel *W*, which by means of a chain *W'* operates both receiving-rollers *K* *L* and the condensing-roller *O*. As shown, the chain 15 passes from wheel *W* over a sprocket-wheel *W²* on the shaft of roller *K*, and thence over a smaller sprocket-wheel *W³* on the shaft of the condensing-roller *O*, and thence over a 20 sprocket-wheel *W⁴* on the shaft of roller *L*, and thence back to the sprocket-wheel *W*.

The cotton is received into the casing through chute *D*, the blast from the ginning machinery being sufficient to carry it through said chute, and it is carried down between 25 the drum and concaved screen by the fingers on the drum, and it is beaten as it is carried along, so as to free it from any dirt or trash by the fingers on the drum, which also loosens the fibers, so that it is thrown upwardly in 30 the casing and over the upper receiving-roller *K*, upon which it falls, and as said roller *K* is rotating in the same direction as the drum it carries the roll down past the drum and between the rollers *K* and *L*, the latter 35 rotating in the opposite direction to roller *K*, and the bat is carried between the roller *L* and condensing-roller *O* and is delivered to the press in an even uniform bat. The fingers act to prevent the cotton coming in contact with the body of the drum and closing or 40 clogging the perforations therein, and thus permits the currents of air from the gin to pass freely through the perforations in the drum at all times. This materially aids in 45 the throwing off of the cotton, since the currents of air from the gin are not broken by the padding down of the cotton on the drum.

Having thus described my invention, what I claim as new, and desire to secure by Letters Patent, is—

50

1. In cotton cleaning and condensing machine, comprising a casing, a beater-drum, a concave screen arranged below said drum, receiving-rollers to receive the cotton from said drum, and a condensing-roller operating 55 in conjunction with one of the receiving-rollers to exert pressure on the bat as it leaves said receiving-rollers.

2. A cotton cleaning and condensing machine, comprising a casing, a drum provided 60 with fingers, a concave screen arranged below said drum, means for adjusting said drum toward said screen, receiving-rollers adapted to receive the cotton from said drum, and a condensing-roller operating in conjunction 65 with one of the receiving-rollers to exert pressure on the bat as it leaves said receiving-rollers.

3. A cotton cleaning and condensing machine, comprising a casing, a drum having 70 beating-fingers secured thereon, a concave screen arranged below said drum and provided with ribs, adjustable receiving-rollers adjacent said drum, and an adjustable condensing-roller operating in conjunction with 75 one of the receiving-rollers to exert pressure on the bat as it leaves said receiving-rollers.

4. A cotton cleaning and condensing machine, comprising a casing, a perforated drum having beating-fingers, a concaved screen 80 having ribs arranged below said drum, means for adjusting said drum toward or from said screen, receiving-rollers, means for adjusting said rollers to and from each other and to and from said drum, a condensing-roller, and 85 means for yieldingly holding said condensing-roller in its adjusted position relatively to one of said receiving-rollers.

In testimony whereof I affix my signature in presence of two witnesses.

EDGAR REAGAN.
